UNITED STATES PATENT OFFICE

THOMAS R. KENNEDY AND JOHN F. HEISTER, OF ROCHESTER, NEW YORK,
ASSIGNORS TO THE COOPERATIVE FOUNDRY COMPANY, OF SAME PLACE.

DESIGN FOR A HEATING-STOVE.

SPECIFICATION forming part of Design No. 27,668, dated September 21, 1897.

Application filed August 12, 1897. Serial No. 648,053. Term of patent 7 years.

To all whom it may concern:

Be it known that we, THOMAS R. KENNEDY and JOHN F. HEISTER, citizens of the United States, residing at Rochester, in the county 5 of Monroe and State of New York, have invented and produced a new and original Design for Heating-Stoves, of which the following is a specification, reference being had to the accompanying drawing, forming a part 10 thereof.

The drawing is a perspective view of a stove, showing our design.

The leading feature of our design consists in the configuration and ornamentation of 15 the stove hereinafter described, and pointed out particularly in the claims at the end of this specification.

A indicates the base of the stove, having the legs *a* and substantially covered by the 20 conventionalized scroll-and-leaf ornamentation shown. Above the base A is the top base-section B, having the scroll-and-leaf ornamentation *b* at the corners and on the front and sides the intermediate ornaments *b'* and 25 *b''*, the spaces between the ornamentation being plain and rounded down to the plain band *b''*, as shown.

The ash-pit section of the stove is provided at the front with the ash-pit door C, having 30 the damper-openings *c* and the ornaments *c'* between them and also having the ornaments *c''* and *c'''* at the ends of the door, as shown. On the sides of the ash-pit section are the plain and rounded rails C', having the flaring 35 ornated ends C'' and supported at the ends upon the ornamental open-work brackets *c''*.

C⁵ indicates the top plate of the ash-pit section, having at the corners the ornaments *c⁵*. 40 The central or body section of the stove has the rounded band or zone D, ornamented at *d*, next to the corner-posts, and beneath this band is the front lower door D', having the six mica openings, the strips *d'* between the 45 openings being ornamented at their intersection, as shown at *d''*. The side lower door D'' is divided by the ribs or strips *d''* into four panels or mica openings and is provided with the ornament *d'''* at the intersection of the 50 ribs. The upper front door E is divided by the ribs or strips *e* into nine mica openings,

and said strips are provided with the ornaments *e'* at their intersection. The upper front door E' is divided into six panels or mica openings by the ribs or strips *e''*, which 55 are provided at their points of intersection with the ornaments *e'''*.

The upper portion of the body-section is somewhat rounded and ornamented by the leaf-and-scroll ornamentation at F. The top 60 section of the stove (indicated by G) is curved upwardly and inwardly at the front and sides, while the corners G' extend downwardly over the corners of the body. This top section G is provided with a horizontal plain band G², 65 above which the upper part G³ is rounded at the edge, and both above and below the band the section is covered with the leaf-and-scroll ornamentation shown.

H indicates the cover, having the plain band 70 H' at the bottom, the rounded surface H² above it covered with the leaf-and-scroll ornamentation, and upon the top of the cover is the urn-like ornament J.

We claim—

1. In a design for a stove, the design for the base, substantially as shown and described. 75
2. In a design for a stove, the design for the top base-section B, substantially as shown and described. 80

3. In a design for a stove, the design for the ash-pit section, substantially as shown and described.

4. In a design for a stove, the design for the ash-pit door, substantially as shown and described. 85

5. In a design for a stove, the design for the central or body section, embodying the front and side doors, substantially as shown and described. 90

6. In a design for a stove, the design for the top section G, substantially as shown and described.

7. In a design for a stove, the design for the cover H, substantially as shown and described. 95

8. The design for stoves substantially as herein shown and described.

THOMAS R. KENNEDY.
JOHN F. HEISTER.
